UNITED STATES PATENT OFFICE.

FREDERICK C. LOWREY, OF WATERBURY, CONNECTICUT, ASSIGNOR TO THE SMITH & GRIGGS MANUFACTURING COMPANY, OF WATERBURY, CONNECTICUT, A CORPORATION OF CONNECTICUT.

PEN AND PENCIL CLIP.

No. 923,055.

Specification of Letters Patent.

Patented May 25, 1909.

Application filed October 5, 1908. Serial No. 456,152.

To all whom it may concern:

Be it known that I, FREDERICK C. LOWREY, a citizen of the United States, residing at Waterbury, county of New Haven, State of Connecticut, have invented certain new and useful Improvements in Pen and Pencil Clips, of which the following is a full, clear, and exact description.

My invention relates to improvements in pen and pencil clips for holding such articles in the pocket, and the invention is particularly concerned with the method of manufacturing the clip spring and to certain features of improvement as will appear from the following description of a preferred form of the invention, which is illustrated in the accompanying drawings, in which—

Figure 1 is a view of the headed wire from which the clip spring is formed. Fig. 2 is a face view of the swaged clip spring blank. Fig. 3 is an edge view of the parts shown in Fig. 2. Fig. 4 is a view of the completed clip spring. Fig. 5 is a front view of the spring and clip assembled. Fig. 6 is an edge view of the parts shown in Fig. 5.

In the embodiment of my invention herein selected for illustration, the clip spring blank 1 (Fig. 2) is formed from a short length of wire 2, which is first headed at one end, as at 3, in any suitable and well known manner. The body of the wire is then swaged flat, as shown, to impart the

necessary resiliency. In the swaging operation two integral securing lugs 4 are preferably formed by which the spring body 35 may be secured to a suitable body, in this instance shown as a clip 5, Figs. 5 and 6.

After the blank is swaged to shape, it is then cut or trimmed to a taper to form the finished spring body or arm 6 (Fig. 4) and 40 when necessary it is at the same time curved transversely to fit the curvature of the back of the clip body member 5. The spring thus formed and the body 5 are then assembled with the lugs 4 projecting through suitable 45 apertures in the back of said clip body, whereupon the lugs 4 are finally riveted down as at 7 (Fig. 5) in said apertures to secure the parts together.

What I claim is:

As a new article of manufacture, a pen or pencil holder comprising a resilient clip body member 5 arranged to embrace a pen or pencil, a holding spring 6, said spring having an integral holding head 3 at one end and an 55 integral rivet 4 near the opposite end and projecting from one face thereof, said clip being secured to said spring by said rivet, said spring being arranged on the outer side of said clip.

FREDERICK C. LOWREY.
